UNITED STATES PATENT OFFICE.

GLENN HENRY BOLUS, OF MANSFIELD, OHIO, ASSIGNOR TO THE OHIO BRASS COMPANY,
OF MANSFIELD, OHIO, A CORPORATION OF NEW JERSEY.

TROLLEY-WIRE HANGER.

1,204,540.

Specification of Letters Patent. Patented Nov. 14, 1916.

Application filed May 12, 1916. Serial No. 97,124.

To all whom it may concern:

Be it known that I, GLENN H. BOLUS, a citizen of the United States, residing at Mansfield, in the county of Richland and State of Ohio, have invented certain new and useful Improvements in Trolley-Wire Hangers, of which the following is a specification.

This invention relates to improvements in suspension devices for trolley wires and the like.

One object of my invention is to provide a hanger for suspending two parallel conductors by means of a single device from a single support.

Another object of my invention is to provide a device for suspending two or more conductors and which can be installed without disconnecting any of the parts, it being merely necessary to loosen the gripping means and to spring the parts away from each other.

With the above objects in view, and the accomplishment of other new and useful objects that will appear, my invention consists in the novel construction, combination and arrangement of the several parts hereinafter more fully described and then claimed.

Referring to the drawings:—Figure 1 is a side elevation of a hanger embodying my invention. Fig. 2 is an elevation view of a hanger embodying my invention taken at right angles to Fig. 1. Fig. 3 is another partial elevation view taken at right angles to Fig. 1 and is intended to show the relation of parts when one jaw is sprung outward to install or remove from the conductors.

In catenary type of construction it is of advantage to suspend the trolley wire more frequently than is ordinarily done when the trolley wire is suspended directly from a messenger wire, as it is possible to maintain a straighter trolley or one with less sag the more frequently it is supported, and to attain this result it is a practice to suspend the trolley by means of short clamps from a wire located just above the trolley wire and to suspend the upper wire from the messenger wire by any of the well known suspension devices. It is also an advantage to use two wires, in that the upper one can be of copper and act as a feed wire to the lower or trolley wire which is, in that case, made of steel or both may be made of copper or steel. I have found, therefore that it is of

advantage to use a suspension device which will grip or clamp on both the trolley and the suspension wire, and to suspend the two from a messenger wire by means of a single suspension device, and as a matter of convenience to so construct the suspension device that it is only necessary to loosen the gripping jaws or clamps and swing them apart in order to place it in position on the wires, thus doing away with loose parts as in the case where it is necessary to disconnect any of the parts in order to install the hanger.

As I construct my hanger, numeral 1 in Fig. 1 represents the messenger from which the hanger is suspended; 2 represents an inverted U shaped strap or suspending member having its ends attached to gripping jaws 3 and 4 by means of rivets 5 which may be either separate from or an integral part of the gripping jaws; 6 and 7 represent a bolt and nut respectively for drawing the gripping jaws tightly into gripping relation with the wires 8 and 9; grooves 10 and 11 are provided in the gripping jaws 3 and 4 for better holding the wires 8 and 9 in position. The gripping jaw 3 is provided with a slot 12 which permits springing the parts away from each other as shown by the dotted line in Fig. 1 and the full lines in Fig. 3 when it is desired to install or remove my hanger and yet not have any loose parts to drop or become lost. Numeral 13 represents a spring lock washer.

To install my hangers, it is only necessary to loosen the bolt and nut 6 and 7, and swing the gripping jaws, 3 and 4, away from each other, place the hanger in position on the messenger cable and place the wires 8 and 9 in position in the grooves 10 and 11 of the gripping jaw 4; swing the clamping member 3 back into place and tighten up the bolt and nut 6 and 7.

While I have described the preferred construction, combination and arrangement of the various parts which go to make up my invention, it will be evident to others skilled in the art that various changes may be made in the above construction without departing from the spirit and scope of my invention, for instance it is possible to adapt my device to the support of a single trolley wire.

What I claim is:—

1. A suspension device for wires consisting of an inverted U-shaped suspension member, a gripping jaw attached to each end of the suspension member and having

parallel wire grooves and arranged to register with each other and means passing between the wire grooves for clamping the gripping jaws in place on the wires.

5. A suspension device for wires consisting of a suspension member, gripping jaws attached thereto and having parallel wire grooves and arranged to register with each other and means passing between the wire 10 grooves for clamping the gripping jaws in position on the wires.

15. A suspension device for wires consisting of a suspension member, gripping jaws attached thereto and normally registering with each other, means for clamping the gripping jaws in normal registering position by an endwise movement of the jaws with respect to each other, means on one gripping jaw permitting the gripping jaws to be 20 thrown out of normally registering position.

25. A suspension device for wires consisting of a suspension member, gripping jaws attached thereto and normally registering with each other, means for clamping the gripping jaws in normal registering position and means on one gripping jaw permitting the gripping jaws to be thrown out of their normally registering position without disengaging the clamping means from more 30 than one jaw.

35. A suspension device for wires consisting of a suspension member, gripping jaws attached thereto and normally registering with each other and a clamping member passing through a hole in one jaw and an open end slot in the other jaw.

40. A suspension device for wires consisting of a suspension member, gripping jaws attached thereto and normally registering with each other, a clamping member passing through the gripping jaws, and means on one gripping jaw permitting disengagement of that member from the clamping member without disengagement of the clamping 45 member from the other gripping jaw.

50. A suspension device for wires consisting of a suspension member, gripping jaws attached thereto and normally registering with each other, the inner faces of the gripping jaws provided with grooves for receiving and retaining wires, clamping means for causing the gripping jaws to be tightened upon the wires and means on one gripping jaw permitting of the member being disengaged from the clamping member without disengagement of the clamping member from the other gripping jaw.

55. A suspension device for wires consisting of a suspension member, a pair of gripping jaws attached thereto and normally registering with each other, the inner faces of each of the gripping jaws provided with parallel wire grooves for receiving and re-

taining the wires, clamping means passing through the gripping jaws and between the 60 grooves for tightening the gripping jaws onto the wires and means on one gripping jaw permitting of that member being disengaged from the clamping member without disengagement of the clamping member 70 from the other gripping jaw.

75. The combination with a messenger cable and two conducting wires of a suspension device consisting of an inverted U-shaped suspension member, a gripping jaw provided with grooves for receiving the conducting wires attached to each end of the suspension member and arranged to have the grooves register, a clamping member passing through the gripping jaws for 80 clamping the jaws onto the wires, and means on one jaw permitting of springing the jaw out of engagement with the clamping member when installing the device and without disengaging the clamping member from the 85 other jaw.

90. A suspension device for wires consisting of a suspension member, gripping jaws attached thereto, clamping means for holding the gripping jaws on the wires and means on one jaw to permit it to be disengaged from the clamping means when installing the device without disengaging the other jaw from the clamping means.

95. A suspension device for trolley wires comprising a suspension member, a two part gripping member for holding the wires, means passing through the two part gripping member for clamping the members onto the wires, an open end slot in one of the 100 parts of the gripping member permitting that part to be disengaged from the clamping means.

105. A suspension device for wires consisting of a pair of gripping jaws normally registering with each other, a clamping member passing through the jaws and means on one gripping jaw permitting disengagement of that jaw from the clamping member without disengagement of the clamping 110 member from the other jaw.

115. A suspension device for wires consisting of a suspension member, gripping jaws attached thereto and having parallel wire grooves and normally registering with each other, means located between the wire grooves for clamping the jaws in normal position and an open end slot in one of the jaws engaging with the clamping means.

120. In testimony whereof I affix my signature in the presence of two witnesses.
